DESIGN FOR A MANTEL OR SIMILAR ARTICLE

Dwight J. Baum, New York, N. Y., assignor to Curtis Companies Incorporated, Clinton, Iowa,
a corporation of Iowa

Application October 18, 1937, Serial No. 72,263

Term of patent 7 years

To all whom it may concern:

Be it known that I, Dwight J. Baum, a citizen of the United States and a resident of New York, in the county of Bronx and State of New York, have invented a new, original, and ornamental Design for a Mantel or Similar Article, of which the following is a specification, reference being had to the accompanying drawing, forming part thereof.

I claim:

The ornamental design for a mantel or similar article substantially as shown.

DWIGHT J. BAUM.
